UNITED STATES PATENT OFFICE.

FREDERICK A. POOLE, OF CHICAGO, ILLINOIS.

ALINING APPARATUS FOR PRINTERS' FORMS.

1,281,830.

Specification of Letters Patent. Patented Oct. 15, 1918.

Application filed July 3, 1916. Serial No. 107,217.

To all whom it may concern:

Be it known that I, FREDERICK A. POOLE, a citizen of the United States, residing at Chicago, in the county of Cook and State of Illinois, have invented certain new and useful Improvements in Alining Apparatus for Printers' Forms, of which the following is a specification.

My invention relates to improvements in alining apparatus for printers' forms and relates more particularly to that class of apparatus of which the device shown in United States patent to Rowse No. 1,133,822, issued March 30, 1915, is an example.

The object of my invention is to provide an apparatus of the class described, so organized that the locking of a number of page forms into a sheet form layout may be accomplished rapidly, accurately, and without the necessity of troublesome mechanical manipulations or mathematical calculations; to provide an arrangement of the class described, the construction of which is such that it will accommodate all sizes of pages having any desired widths of margin without the necessity of substituting or changing parts of the apparatus or using different sized appliances; to provide a construction which is simple and economical to manufacture; and, in general, to provide an improved construction of the character referred to.

In the drawings which illustrate a preferred embodiment of my invention—

Figure 1 is a plan view of a lock-up stone equipped with my improvements;

Fig. 2 is a section taken on the line 2—2 of Fig. 1;

Fig. 3 is a plan view of one of the adjustable mountings for the alining guides;

Fig. 4 is a section taken on the line 4—4 of Fig. 3;

Fig. 5 is a fragmentary enlarged view of the left-hand end of Fig. 4;

Fig. 6 is a section taken on the line 6—6 of Fig. 3;

Fig. 7 is a perspective view of the gage bar; and

Fig. 8 is a fragmentary side elevation of Fig. 1.

Referring to the drawings, 10 represents the lock-up stone or imposing plate which forms a bed or table upon which the alining and registering of the forms is carried out.

Said lock-up stone is a substantial cast iron rectangular slab suitably supported at a con-

venient height, for instance, upon a printer's cabinet, and planed off smooth on its upper surface. The chase in which the page forms are to be locked up to constitute a sheet form 60 is indicated at 11 and the page forms (in the present case sixteen in number to form a sixteen-page book) are indicated at 12 to 27, inclusive. In the drawing I have shown the page forms locked up in the chase, but of course it should be understood that said forms are not finally locked up in the chase until the alining apparatus has been utilized to accurately position the page forms.

Around three sides of the plate are permanently secured by cap screws or other devices three flat bars 28, 29 and 30 which project above the surface of the lock-up stone, as shown in Fig. 2. On the right-hand side of the plate there is also detachably mounted a similar flat bar 31 which may be removed from the stone by slackening off the cap screws 32, 33, 34 and 35, thereby enabling the bar 31 to be lifted vertically upward and removed bodily. The devices which constitute the 80 important part of my invention are carried on the upwardly projecting portions of the bars 28, 29, 30 and 31. 36 represents a longitudinal mounting block made of machine steel or other suitable metal, in the under 85 side of which is cut a groove 37 which fits over the upper edge of one of the edge bars 28, 29, 30 or 31. Midway of the length of the block a threaded hole accommodates a set screw 38 with a milled head 39 by which 90 the position of the mounting block 36 along the edge bar may be adjusted and held. In the upper face of the mounting block is cut a rectangular groove 40 the ends of which are closed, the top of the groove being open 95 to accommodate the sliding alining guides or gages 41 and 42. Said gages 41 and 42 are rectangular in order to fit and slide in the groove 40. As shown in Fig. 6, the upper ends of the gages 41 and 42 project above 100 the level of the top of the mounting block 36 and are inclined downwardly toward the lock-up stone and are provided with saw cuts 43 in order to accommodate alining strings, as shown at 44.

The gage blocks 41 and 42 are tapped respectively with a left-hand and a right-hand thread in order to accommodate corresponding left-hand threads 45 and right-hand threads 46 on a micrometer screw 47. As 110 shown best in Fig. 4, said micrometer screw is reduced at its right-hand end to form a

- small journal 48 which rotates in the end 49 of the mounting block. The other end of the screw is similarly reduced, as shown at 50 in order to furnish a journal rotatable 5 in the other end 51 of the mounting block 36. Longitudinal axial movement of the micrometer screw 47 is prevented by reason of the shoulders at the ends of the screw threads which engage the opposed inner 10 faces of the slot ends 49 and 51. Rotation of the screw for adjusting purposes is accomplished by means of the knurled head 52 which is secured upon the extended end of the stem 50 by means of a diametric pin 53.
- 15 Improper movements of the adjusting screw are largely prevented by means of a conical headed pin 54 arranged to slide in a short cylindrical bore 55 under the influence of a coil spring 56 which forces the conical head 20 57 of the pin 54 into one or other of a pair of diametrically opposed conical recesses or countersinks 58 in the end of the mounting block 36. It will of course be readily understood by those skilled in the art that the 25 mounting block 36 must be made in two or more parts in order to permit the insertion of the micrometer screw, although it is unnecessary to describe such sectional construction in detail.
- 30 Each of the gage block mountings 36 is provided on its upper surface with a scale 59, preferably in inches and sixteenths, the zero point of which coincides with the center of a gage hole 60 positioned centrally 35 between the said kerfs 43 and gage blocks 41 and 42. Such symmetrical relation of the blocks 41 and 42 with reference to the gage hole 60 is always maintained by reason of the fact that the threads 45 and 46 40 have the same pitch, each of the blocks therefore moving an equal amount to or from the center when the milled collar 52 is turned.
- In using the apparatus, the page forms 45 are roughly placed in position on the lock-up stone, the bar 31 is applied, and a pair of strings are stretched across the permanent or end gage blocks 61, 62, 63 and 64. These end gages 61, 62, 63 and 64 are single-ended 50 since they accommodate only one string, and are so positioned that the strings 65 and 66 cross each other exactly at right angles when the gage blocks on said end mountings are properly adjusted. Scales are 55 marked on the end blocks 61, 62, 63 and 64 similar to the scales 59 on the double gage mountings, gage holes being also drilled at the zero points of said scales.
- In setting the strings 65 and 66 the operator, by means of the micrometer screws, 60 adjusts the gage blocks in such position that the strings or saw cuts in the gage blocks will be located at distances from the gage holes corresponding to the allowance to be 65 made for margin and trimming between the edge of the paper and the boundary of the printing area. Having properly adjusted the gages 61, 62, 63 and 64 for the strings 65 and 66, the operator sets the gage bar 67, Fig. 7, to the proper distance between 70 the edge of the sheet which is to be printed and the point where the first fold of said sheet is to be located. Said adjustment of the gage bar 67 is effected by means of a sliding clamp 68 which may be set by a knurl 75 screw 69 according to a scale 70. The fixed gage pin 71 is then inserted in the end block 64 and the properly adjusted slideable gage pin 72 is inserted in the mounting 36 by sliding the latter along the edge bar 29 80 until it is in such position as to permit the entrance of said gage pin 72. The thumb screw 38 is then turned to clamp the mounting 36 securely in position on said bar. The other gage block mountings on the side 85 edges of the plates are similarly clamped in position, after which the adjustment of the gage bar is changed to correspond with the width instead of the length of the page, after which the end gage block mountings 90 are clamped in position. Having thus utilized the gage bar 67 to set the gage block mountings around all four sides of the lock-up frame, strings are stretched in the kerfs of the gage blocks and the micrometer 95 screws are adjusted so as to lock each string a distance from the gage hole which corresponds to the allowance to be made for margin and trimming. It will be readily understood that the strings will then occupy the 100 positions shown in Fig. 1, thus enabling the page forms to be locked up into proper registering position, as shown.
- In view of the foregoing, it will be seen that my construction is of great benefit and 105 advantage to the practical printer in enabling him to lock up a large number of page forms in each chase with a minimum of trouble or opportunity for mistakes. Provided that the preliminary location of the 110 gage block mountings has been properly effected, which is an easy matter with the gage bar, the only thing then necessary is to adjust all of the micrometric mountings 115 an equal amount. With my improved micrometric gages there is no possible opportunity for locking the gage strings at different distances from the fold in the paper, assuming of course that the printer has properly calculated the distance between 120 folds and has set his gage bar accordingly. The manipulation of the apparatus will be found to be extremely rapid, accurate, and efficient, and in practice results in marked 125 economy.
- The invention is not necessarily confined to use in connection with lock-up stones, but may conceivably be used in connection with other devices or apparatus by means of 130 which the page forms are locked up into a

sheet form. The term "lock-up frame" as used in the claims is intended to cover all devices designed for the general purpose of a lock-up stone as used in connection with a chase. I consider within the scope of my invention any arrangement by which the gage-string supports are properly coördinated with the chase or holder for the forms. Such lock-up frame on which the gage-
10 string supports are founded need not necessarily include the lock-up stone as ordinarily employed.

The described details of construction merely illustrate the application of my invention, the scope of which must be determined by reference to the appended claims.

I claim—

1. In combination, a lock-up frame, a mounting device located at either side of said lock-up frame, a pair of gage string supports mounted upon each of said devices, and means for simultaneously moving the pair of supports on each of said devices in opposite directions.

2. In combination, a lock-up frame, two adjustable mounting blocks, means for securing said blocks in a plurality of positions on opposite sides of said frame, a pair of gage string supports on each of said blocks, and means associated with each of said blocks for simultaneously adjusting both of said supports thereon.

3. In combination, a lock-up frame, a pair of mounting blocks movable along the opposite sides of said frame, a pair of gage string supports movably mounted on each block, and screw means for effecting simultaneous movement of both of said supports in opposite directions on each of said blocks.

4. In combination, a lock-up frame, a pair of gage string supports mounted to slide along each of two opposite sides of said frame and screw means for simultaneously effecting sliding movements of a plurality of said supports.

5. In combination, a lock-up frame, a pair of gage string supports mounted to slide along each of two opposite sides of said frame, and screw means for simulta-

neously adjusting a pair of supports on the same side of said frame.

6. In combination, a lock-up frame, a pair of gage string supports mounted to slide along each of two opposite sides of said frame, and screw means for simultaneously adjusting a pair of supports on the same side of said frame in opposite directions.

7. In combination, a printer's lock-up stone, bars secured to opposite sides of said stone, mounting blocks slidably mounted on said bars, means for locking said blocks to said bars, a pair of gage string supports slidably mounted upon each block, and a screw provided with right and left hand threads carried by the block and engaging said supports.

8. In an alining apparatus for printers' forms, the combination of, a lock-up stone, a pair of mounting blocks adjustably mounted at opposite sides of said stone, a screw provided with right and left hand threads and axially positioned in each block, and a pair of gage string supports slidably mounted on each block and respectively engaging the right and left hand threads of said screw.

9. In an alining device for printers' forms, the combination of, a lock-up stone, bars secured to the opposite sides of the stone, a mounting block slidably mounted on each bar, means for locking said block to said bar, a pair of gage string supports slidably mounted in said block, a screw provided with right and left hand thread engaging said supports and carried by said block, and means for preventing improper movement of said screw.

10. In an alining apparatus for printers' forms, the combination of, a lock-up stone, bars secured to the four sides of said stone, a plurality of mounting blocks slidably adjustable on each of said bars, means for securing said blocks in any desired position and a pair of gage string supports slidably adjustable on each of said blocks.

FREDERICK A. POOLE.
